UNITED STATES PATENT OFFICE.

CHARLES E. PIERCE, OF CAMBRIDGE, MASSACHUSETTS.

CAN-CLOSING DEVICE.

SPECIFICATION forming part of Letters Patent No. 546,078, dated September 10, 1895.

Application filed May 13, 1895. Serial No. 549,094. (No model.)

To all whom it may concern:

Be it known that I, CHARLES E. PIERCE, of Cambridge, in the county of Middlesex and State of Massachusetts, have invented certain new and useful Improvements in Can-Closing Devices, of which the following is a specification.

This invention relates particularly to sheet-metal cans which inclose articles of food, and has for its object to provide a can of this class adapted to be conveniently opened without recourse to a cutting-tool.

The invention consists in a can having a discharge-opening surrounded by a flat seat or surface which is a part of the external surface of the can, and a flexible sheet-metal cover secured to said seat by a film of solder disposed only between the cover and the seat, the edges of the cover being outside of said film, and the said cover having an outwardly-projecting tongue adapted to be engaged with a key, so that by rotating the key first the tongue and then the cover will be rolled upon the key, the solder-film being thus gradually broken until the cover is removed, thus exposing the opening.

Of the accompanying drawings, forming a part of this specification, Figure 1 represents a top view of a can provided with my improvement. Fig. 2 represents an enlarged section on line 2-2 of Fig. 1. Fig. 3 represents a section similar to Fig. 2, showing the operation of removing the cover. Fig. 4 represents a side view of the key employed to remove the cover. Fig. 5 represents a sectional view of a somewhat different construction.

The same letters of reference indicate the same parts in all the figures.

In the drawings, *a* represents a sheet-metal can, which may be of any suitable form and construction, and has at a suitable point, preferably in one of the heads of the can when the latter is of cylindrical form, an opening *a'*, through which the contents may be removed or discharged, said opening being surrounded by a seat *a²*, which is a part of the external surface of the portion in which the opening *a'* is formed.

b represents a cover, composed of a flat piece of flexible sheet metal formed to extend across

the opening *a'*, the said cover being considerably larger than the opening, so that it will bear upon the seat *a²* entirely around the opening, and thus effectually close the latter. The cover *b* is secured to the seat *a²* by a film of solder interposed between the inner surface of the cover and the seat, but not extending outside of the cover, the edges of the cover being outside the film of solder and free from engagement therewith, the object being to form an air and liquid tight connection between the cover and the seat, and at the same time make a connection which will be easily rupturable by the operation of rolling the cover into a scroll, as hereinafter described. The cover *b* is provided with a tongue *b'*, which is integral with the cover and projects from one edge thereof, the tongue being therefore flexible like the cover. The tongue *b'* may be bent back upon the cover *b*, as shown in Figs. 1 and 2, when its use is not required.

c represents a key, which may consist of a flat piece of metal having a slot *c'* in one end of sufficient size to receive the tongue *b'*.

When it is desired to open the can the key is placed upon the tongue *b'*, said tongue entering the slot *c'*, and the key is then rotated, thus first winding the tongue upon the key in the form of a scroll, and then as the scroll approaches the body of the cover gradually rupturing the solder connection between the cover and seat and rolling the cover upon the key in continuation of the scroll, this being continued until the cover is detached from the seat, thus exposing the opening *a'*.

I prefer to make the seat *a²* wider under that part of the cover from which the tongue extends than elsewhere, in order that the solder connection between the cover and seat may be stronger at said point, the object of this being to prevent the cover from suddenly breaking away from the seat along a considerable portion of its length when the tongue has been nearly all rolled upon the key. I find that when the seat is of a uniform width entirely around the opening the cover does not roll as uniformly and evenly as when the seat is made wider under the part of the cover from which the tongue projects.

In order to form a sufficiently strong and

tight solder-joint between the cover and the seat, a considerable degree of pressure is required, since the quantity of solder used is necessarily limited. I therefore form the seat a^2 on a bushing-piece d , which is a piece of sheet metal of sufficient size to contain the opening a' and form the seat a^2 and to project sufficiently outside of said seat to admit of its being soldered in the usual way to the head a^4 of the can, said head having an enlarged opening formed to be covered by the bushing d . In practice, the cover b will be secured to its seat on the bushing d before the solder is applied to the can, so that the two parts can be conveniently subjected to the pressure required in forming the solder connection between the cover and its seat. The can is filled through the opening in its head before the bushing is applied, and when the can is ready for soldering the bushing is applied and soldered to place in the usual manner by a solder joint a^4 externally applied.

In Fig. 5 I show the bushing d provided with a screw-threaded offset portion d' in which the discharge-opening a' is formed, the seat a^2 being at the outer end of the said offset portion. A screw-threaded sheet-metal cap d^2 is engaged with the offset portion d' and serves to protect the tongue b' , the latter being bent back and inclosed in the space between the seat a^2 and head of the cap d^2 .

It will be seen that my improvement enables a can to be quickly opened without the use of a can-opener.

In Fig. 6 I show as an equivalent of the bushing d a bushing or cap d^2 , formed to be permanently secured by cement or otherwise to the neck n of a glass jar or can, said bushing d^2 having a discharge-opening d^3 surrounded by a seat to which a flexible sheet-metal cover b is applied, said cover being secured to its seat in the manner above described and provided with a tongue b' . I do not, therefore, limit

myself to the described improvement in connection with a metal can or receptacle.

45

I claim—

1. A can comprising a body having an enlarged opening surrounded by a seat or bearing surface, and a two-part closing device comprising, first, a bushing formed to bear at its outer portion on said bearing surface and adapted to be united thereto by a sealing medium during the operation of sealing the can, said bushing having a smaller opening surrounded by a seat projecting inwardly from the margin of the opening in the can body; and secondly, a cover formed to close the opening in the bushing and to bear on the seat on the bushing, said cover being secured to the bushing by a rupturable film of solder interposed between the bushing and cover and provided with an outwardly projecting tongue whereby it may be rolled back to separate it from the bushing, said bushing and cover constituting a closing device adapted to be secured to the can by the operation of sealing the latter, and to be easily ruptured to afford access to the interior of the can.

2. A can comprising a body having an enlarged opening, a bushing secured to the body around said opening, said bushing having a screw-threaded offset and a seat at the outer portion of said offset surrounding a discharge opening in the offset, a flexible sheet-metal cover soldered to said seat and provided with a flexible tongue, and a screw-threaded cap adapted to inclose said offset and cover the tongue.

In testimony whereof I have signed my name to this specification, in the presence of two subscribing witnesses, this 24th day of April, A. D. 1895.

CHARLES E. PIERCE.
